UNITED STATES PATENT OFFICE.

HENRY B. SARGENT, OF NEW HAVEN, CONNECTICUT, ASSIGNOR TO THE SARGENT & COMPANY, OF SAME PLACE.

DOOR-HOLDER.

SPECIFICATION forming part of Letters Patent No. 613,427, dated November 1, 1898.

Application filed June 17, 1898. Serial No. 683,674. (No model.)

To all whom it may concern:

Be it known that I, HENRY B. SARGENT, of the city and county of New Haven, in the State of Connecticut, have invented a new and useful Improvement in Door-Holders, of which the following is a full, clear, and exact description when taken in connection with the accompanying drawings, which form a part thereof, and in which—

10 Figure 1 represents a side elevation of a door-holder embodying the invention; Fig. 2, a similar view with the parts in altered position; Fig. 3, a reverse of the same with the spring omitted, and Fig. 4 a transverse sectional view on lines 4 of Fig. 3.

15 In all figures similar numerals of reference represent like parts.

This invention relates to door-holders; and it consists in the novel construction described 20 and claimed hereinafter in that particular class of holders adapted to hold a door in any desired position.

25 The object of the improvement is increased simplicity and economy in construction and efficiency in use.

In the drawings the part designated by the numeral 1 represents the lower portion of a door to which the holder is attached.

30 The holder consists, primarily, of three parts—the plate 2, attached to the door by screws or other means through the screw-holes 5, the lever 3, pivoted to the plate 2, and the coiled spring 4, connected to the lever 3 and plate 2.

35 The plate 2 may be of any desired outline, though shown here of general semicircular form. An inwardly-extending flange 6 on the periphery of the plate 2 forms, with the inner surface of the plate, a hollow space, as 40 shown in Fig. 4, when the plate is secured to the door 1. At the lower edge of the plate is a substantially semicircular slot or opening 7, and on the inner surface of the plate is a second inwardly-extending or guide flange 8 45 concentric with the semicircular slot 7.

The lever 3 is formed hollow or semicylindrical, as shown at 20, broken away in Fig. 2, and is provided at one end with a rubber or other suitable washer or cushion 9, secured 50 thereto by rivet, screw, or other suitable means. At about the middle of the length

of the lever 3 is a lateral lug or arbor 10, adapted to bear in and extend through the semicircular slot 7. At the other end of the arbor 10 is formed integral therewith or rigidly secured thereto a flat guide-disk 11. The plane of the guide-disk 11 extends parallel to the line of the lever 3, and the disk is provided with a slot or groove 12, corresponding with and adapted to receive the guide-flange 8. 60

The spring 4 is connected at one end to a lateral projection 13 on the end of the plate 2 and at the other to the lever 3 at or near the point of union of the lever and cushion 9. A slot 14 and cross-piece 15 are shown in 65 Fig. 4, by means of which the end of the spring 4 may be secured to the lever. As the points of union between the spring 4 and lever 3 and plate 2, respectively, are on opposite sides of the fulcrum of the lever and 70 plate when the lever is turned in any position other than shown in Fig. 1 (where a dead-center is maintained) to such a position as shown in Fig. 2 the spring tends to draw the end of the lever carrying the cushion toward the end of the plate having the lateral projection; but as the plate is affixed to the door the end of the lever, with the cushion, 75 is swung downward and comes in contact with the floor and by means of friction holds the 80 door in a fixed position.

The parts of the device are readily assembled. The guide-flange 8 terminates at a point 16, so that the guide-disk 11, with the groove 12, may be passed on or off the rear of the plate 2 when the arbor 10 is fitted into the slot or opening 7. The disk is turned so that groove 12 engages the flange 8 and the spring secured to the lever and plate, when the whole device may be attached to the door. 90

Having now described my invention, what I claim, and desire to secure by Letters Patent, is—

1. In a door-holder, the combination with a plate adapted to be affixed to the door having an inwardly-projecting flange, arranged on the arc of a circle of a lever pivotally mounted on said plate; a spring connected to said plate and lever on opposite sides of the fulcrum-point of said lever, and a guide-disk 95 rigidly connected to said lever on the opposite side of said plate having a groove for en- 100

gagement with the flange on said plate, substantially as described.

2. In a door-holder, the combination with a plate adapted to be affixed to the door, having a hollow space between it and the door when so affixed; of a lever pivotally mounted on the outer side of said plate; a spring secured to said plate and lever on opposite sides of the fulcrum of said lever; a guide-disk rigidly connected to said lever and located in

the hollow space between said plate and door; and means by which said disk is held in engagement with said plate during the operation of said device, substantially as described.

In witness whereof I have hereunto set my hand this 14th day of June, A. D. 1898.

HENRY B. SARGENT.
